UNITED STATES PATENT OFFICE.

GEORGE W. FOSTER, OF PROVIDENCE, RHODE ISLAND, ASSIGNOR TO UNIVERSAL WINDING COMPANY, OF BOSTON, MASSACHUSETTS, A CORPORATION OF MASSACHUSETTS.

WINDING-MACHINE.

1,309,404.

Specification of Letters Patent.

Patented July 8, 1919.

Application filed July 3, 1917. Serial No. 178,393.

To all whom it may concern:

Be it known that I, GEORGE W. FOSTER, a citizen of the United States, residing at Providence, in the county of Providence, State of Rhode Island, have invented certain new and useful Improvements in Winding-Machines, of which the following is a specification.

My invention relates to winding machines and particularly to cone-winders of the drum- or friction-driven type. It has for its object to provide an improved mechanism for winding yarn or other textile materials into conical packages while building the cones with a gradually increasing taper from their inner to their outer layers, whereby to insure a free and unrestricted delivery of the yarn in unwinding it therefrom. The peculiar method of building the cone to secure this increasing taper on its surface from its interior to its exterior consists essentially in periodically stepping back the courses of the yarn-coils at intervals of the winding to dispose a thicker mass of material at the base of the cone than at the apex end. This method is disclosed in my U. S. Letters Patent No. 1,233,041, dated July 10, 1917, and one form of traverse-mechanism for effecting the shortening and lengthening of the throw of the thread-guide, which deposits the yarn-coils in place on the cone, is described and illustrated in my U. S. Letters Patent No. 1,233,042, dated July 10, 1917.

My present invention is directed to the winding-mechanism in general and consists of improvements in the structure and method of operation of the complete machine as fully described in the following specification, illustrated by the accompanying drawings, in which like reference characters designate like parts. In the drawings:

Figure 1 is a front elevation of a portion of the machine frame or stand, showing the arrangement of the several winding-units mounted thereon;

Fig. 2, an end view of the frame, showing the driving-connections between the main operating-shafts;

Fig. 3, an enlarged, detail view of the main traverse-mechanism of the machine shown in relation to one of the winding-units;

Fig. 4, an end elevation of the same; 55
Fig. 5, a plan view of the cone-holder supporting-means;

Fig. 6, a side view of the same, part sectional on the axes of the cone-holder supporting arms; 60

Figs. 7 and 8, detail views of the same; 65
Fig. 9, a longitudinal, sectional view of the cone-tube, showing the means for rotatably supporting it in relation to the drive-roll or drum;

Fig. 10, a detail view of the cone-lifter shown in connection with the coördinated stopping-mechanism of the machine; and

Fig. 11, a longitudinal, sectional view of the cone-lifter, showing its relation to the 70 drive-roll.

Referring first to Figs. 1 and 2, my improved machine is preferably constructed in gang form with a plurality of winding-units mounted on a stand or frame F. 75 The frame F may be of any suitable construction and as here illustrated comprises the longitudinal rails or side-members 2, 2 supported at their ends by standards 3 provided with feet, not here shown, which may be bolted to the floor on which they stand. Journaled in bearings 4 bolted to the end-frames 3 is the main drive-shaft S which extends the whole length of the machine. On the outer end of the drive-shaft S are 80 tight and loose pulleys P, P' which may be connected by a belt, not here shown, to the motor or other prime-mover from which the machine is driven. A shipper-fork U, see Fig. 2, is slidable on a rod 5 and may be 85 operated by the handle U' to shift the belt from the loose pulley P' to the tight pulley P, and vice versa, to start or stop the machine. Fast on the shaft S at the opposite side of the end-frame F is a gear 6 meshing 90 with a larger gear 7 which is keyed or otherwise secured on an upper shaft S'. The shaft S' is journaled at its outer end in a bearing 8 bolted to the standard 3, and extends through bearings 9, 9 in two brackets 100 H, H which depend from the side-rails 2, 2. As shown in Figs. 3 and 4 the brackets H, H are formed with arms 10, 10 which overlap the top of the side-rails 2 and are bolted thereto. At their lower ends the 105 brackets H, H are connected by a drip-pan H' so that the whole structure forms a sort of casing or housing for the traverse-cam K.

which is mounted fixedly on the upper shaft S'. Preferably the housing H, H' is mounted on the side-rails 2, 2 midway between the end-frames 3 and the single cam K serves 5 as the main driving element for the whole series of thread- or yarn-guides G which are reciprocated on opposite sides of the machine in juxtaposition to the cone-holders C spaced therealong.

10 Referring again to Figs. 1 and 2, the end-frames 3 are provided with bearings for two horizontal shafts R, R' which carry the friction-drums or drive-rolls D, D, etc. The shafts R, R' are arranged in parallel 15 relation on opposite sides of the machine and rotate in bearings 12, 12 bolted to the top of the side-rails 2, 2. They are driven from the main drive-shaft S by means of a chain V passing over the sprockets 13, 14 20 and 15. The sprocket 14 is fast on the end of the shaft R to provide a direct drive therefor, but the sprocket 16 is rotatable on a stud-shaft 16 and carries a gear 17 which meshes with a gear 18 on the shaft R'. 25 Through this arrangement the shafts R, R' are driven in opposite directions as required to rotate the drive-rolls D in the manner and for the purpose as hereinafter more fully explained. An idler-sprocket 20 30 is journaled on a shaft 21 at the end of an arm 22 and the driving chain V passes over it, as shown in Fig. 2, to take up the slack. The arm 22 is pivoted on a stud 23, screwed into the side of the end-frame 3, 35 to adapt it to be swung about the axis thereof to adjust the position of the idler 20. A bolt 24 reaches through an arcuate slot 25 in the arm 22 and extends through a hole in the frame 3 with a nut 26 at its end. The 40 nut 26 may be loosened to adapt the arm 22 to be adjusted on its pivot 23 and by tightening it again the bolt 24 will act to clamp the arm in position against unwarranted movement.

45 Extending horizontally the length of the machine is a tie-rod T secured at its ends in bearings at the top of the frames 3, 3, see Figs. 1 and 2. Spaced at intervals along the rod T are a plurality of depending 50 brackets 28, 28, which support a lower, parallel rod T', see also Figs. 4, 5 and 6. The brackets 28, 28 are extended below the rod T', and secured therein are pins or studs 29 on which are pivotally mounted the 55 swinging arms A for supporting the small ends of the cone-tubes or mandrels C on which the packages are wound, see Figs. 4 to 6. The opposite or base end of each cone-tube C is supported by an arm B which 60 is pivoted on the rod T'. Through this arrangement the larger or base end of the cone is caused to swing about an axis elevated above the axis of the pivot about which the small or apex end swings in the 65 manner as later described. Each arm B is

formed with a hub 30 which is rotatable on the rod T' and free to slide thereon against the tension of a coiled spring 31. As shown in Figs. 5 and 6 the arms B, B' are arranged in pairs disposed in opposite relation between each pair of brackets 28, 28. The arm B of each pair supports the base end of the cone-tube C at one side of the machine while the other arm B' extends in the opposite direction to support the cone-holder on the 70 other side of the machine. The arms B and B' are located in position longitudinally of the rod T' by means of collars 32, 32 secured to the rod T by set-screws 33. Each collar 32 is formed on its side with an inclined cam-face 34 against which a lug 35 on the hub 30 of the arm B rides, see detail view, Fig. 8. The lug 35 is formed on the side of a flange 36 at the end of the hub 30, and bearing against the opposite side of the 80 flange is a plate or washer 37 which takes the thrust of the spring 31. The washer 37 is formed with spaced arms 38, 38, see Fig. 7, which straddle the sides of the upper rod T to hold the washer from turning. As 85 shown in Fig. 6 the spring 31 acts against the hubs 30 of both arms B and B' to maintain their lugs 35 bearing against the cam-faces 34, and the purpose of the washers 37 is to prevent the swinging movement of the 90 arm B from tending to wind or unwind the spring 31. The arms B, B' are caused to swing upwardly on the rod T by the recession of the cone-holders C from the drive-rolls D during the growth of the package, 95 see Fig. 4. As the arm B swings upwardly about the axis of the rod T' the lug 35 will ride outwardly on the incline 34 of the collar 32 to slide the arm bodily to the right against the action of the spring 31. Likewise, the upward movement of the arm B' will cause its lug 35 riding on the incline 34 of the collar 32 to slide the arm to the left on the rod T'. Through this arrangement the cone-holders C are caused to be 100 displaced longitudinally of their respective drive-rolls in a substantially axial direction. This axial displacement of the cone is in the direction of its apex end and is relatively slight, being designed to overcome the tendency of the cone to build up 105 with an excessive concavity at its nose. This tendency arises from the inclined relation of the axis of the cone to the surface of the drive-roll and in the present type of machine 110 this inclination becomes greater as the cone builds up with an increasing taper of its surface. The purpose of the above described arrangement for shifting the cone along its drive-roll is more fully explained 115 in my pending U. S. application for patent, Serial No. 124,373, filed Oct. 7, 1916, the present mechanism embodying certain improvements in the structure and method 120 of operation of the device.

Referring still to Figs. 5 and 6, the apex or nose end of each cone-holder C is supported at the end of the before-mentioned arm A, which carries a bearing arranged as follows: Pivoted on the stud 29 which projects from the side of the bracket 28 is a hub 40 held between the side of the bracket and the cap-like bearing 41. The cap 41 is formed with a nut 42 screwed onto the reduced end 43 of the stud 29 and locked in place by a check-nut 44. The inner face of the cap 41 is concaved to receive a relatively thin, dished spring-washer 45 which bears against the side of the hub 40, thereby tending to regulate the swinging movement of the arm A about its axis. That is to say, the spring 45 acts to frictionize the turning of the hub 40 on the stud 29 and thereby serves to resist the movement of the arm A as the nose of the cone recedes from the drive-roll. The purpose of this arrangement is to insure a firm contact of the nose end of the cone against the drive-roll D which imparts rotation thereto. As shown more particularly in Fig. 5, the hub 40 is formed with a short arm 46 to the side of which is hinged the main arm A. The arm A is connected to the arm 46 by a pivot-pin 47 and is formed with a pocket 48 for receiving the end of a helical spring 49. The opposite end of the spring 49 bears against the side of the arm 46 to maintain the end of the arm A in position to receive the apex or tip of the cone-holder C, while also providing for the axial displacement of the cone when the arm B is slid along the rod T', as previously explained. As shown in Figs. 5 and 6 each stud 29 supports a pair of hubs 40 for two oppositely extending arms A, A', the latter supporting the cone-holders of two winding-units on opposite sides of the machine.

Referring now particularly to Fig. 9, the cone-holder C is preferably of conventional form consisting of a conical tube having relatively thin walls, usually of paper or fiber, converging at one end in the rounded nose c. The nose c is adapted to be fitted into a cup-like member 50 mounted in a ball-bearing at the end of the arm A. Any suitable form of bearing may be employed for this purpose and as here shown the cup 50 carries a ball-race 51 on its periphery adapted to engage a series of balls 52 rolling in a corresponding race 53 held in an opening 54 in the end of the arm A. The opposite, base end of the cone-tube C fits over the tapered periphery of a ring or bearing 55 which is formed with a hub 56 carrying a ball-race 57. Projecting from the side of the arm B is a stud 58 formed with a head 59 having its inner side concaved. The stud 58 is inserted through the bore 60 of a sleeve 61, the outer end of which is of convex formation to adapt it to fit the concavity of the head 59. The inner end of the sleeve 61 is slightly enlarged in a flange 62 having its side formed convexly to adapt it to fit into a corresponding concavity 63 in the arm B. On the periphery of the sleeve 61 is a ball-ring or race 64 arranged opposite the race 57 with the balls 66 revolving therebetween. A cap 67 is screwed onto the sleeve 61 to hold the race 64 in place against a shoulder 68, said cap being formed with a flange 69 for retaining the bearing-ring 55 in position with the balls 66 in proper relation to the races 57 and 64. It will be noted that the bore 60 of the sleeve 61 is of greater diameter than that of the stud 58 to provide sufficient play for the sleeve to rock slightly on its bearing. That is to say, the sleeve 61 which carries the bearing-ring 55 is free to move in the manner of a ball-and-socket joint, the purpose of the arrangement being to allow the cone C to change its angle of inclination to the driving-drum D as it recedes therefrom with the growth in the winding.

Referring now to Figs. 1 and 4, the arm B is slotted along its top at 70 and pivoted in the slot on a cross-pin 71 is a lever 72. The outer end of the lever 72 is provided with a finger-piece 73, while its inner end is formed with a hook 74, the extremity of which normally rests on the top of the tie-rod T. As the arm B swings upwardly during the building of the cone the end of the hook 74 rides around the periphery of the rod T without interfering with the movement of the arm. When, however, it is required to raise the cone away from contact with the drive-roll D in piecing up the yarn or in applying the cone-tube C to its holder and in doffing the completed package, the arm B is lifted far enough to allow the end of the lever 72 to hook around the rod T. Through this means the arm B may be suspended in raised position to facilitate the application of the cone-tube C to the supporting arms A and B and the removal of the completed package; and by pressing down on the outer end of the lever 72 its hook 74 can be released to allow the arm to be lowered into operative position as shown in Fig. 4. A weight W, shown in Fig. 4, is usually attached to the side of the arm B to maintain the cone or package firmly against the surface of the drive-roll D during the winding, this element being omitted from the other views so as not to confuse the showing of the other parts.

The thread-guides G which operate to traverse the yarn or thread back and forth along the cone-tubes C during their rotation from the drive-rolls D are carried by two longitudinally reciprocable traverse-bars E mounted on opposite sides of the machine. The bars E are preferably of rectangular shape in cross-section and are mounted to slide in slotted bearings 75 which are formed

as extensions of the bearings 12 for the drive-roll shafts R, R', see Figs. 2, 3 and 4. The guides G are constructed of sheet-metal formed to fit around the sides of the bars E and secured in place by screws 76. Each guide G has an arm 77 reaching in toward the drive-roll D with its end bent upwardly at a point adjacent the line of contact of the cone-tube C on the surface of the roll. Formed in the top of the guide G is a slot g, see Fig. 3, for receiving the yarn or other strand to be wound onto the tube C. Each traverse-bar E carries a plurality of thread-guides G equal in number to the whole number of winding-units on its respective side of the frame F. As before stated a single cam K serves to traverse all of the thread-guides on both sides of the machine, and this is connected to reciprocate the two traverse-bars E as next described.

As both traverse-bars E have the same arrangement of connection with the cam K it will suffice to explain the mechanism for one only, reference being had particularly to Figs. 1, 3 and 4. The cam K is mounted fast on the upper shaft S' between the brackets H, H, and is of usual construction having a hub 80 with spokes 81 radiating therefrom to support the circular rim 82. In the rim 82 is a helical groove 83 adapted to receive a roll 84 which is rotatable on a stud 85 projecting from the side of a slide or crosshead 86, see Fig. 4. The crosshead 86 slides on two rods or tracks 87, 88 extending between the sides of the brackets H, H. For the lower track 87 a round rod is employed, adapted to fit the circular bores 89 of two bearings 90, 90 at the ends of the oppositely extending arms 91, 91 of the crosshead 86. At the top of the crosshead 86 is a central bearing 92 formed with a rectangular slot 93 fitted to the sides of the upper, square rod or track 88. The stud 85 which carries the cam-roll 84 is bored axially to receive a smaller stud or pivot-pin 94 which projects from the side of a bell-crank-lever L to connect the latter pivotally with the crosshead 86. The bell-crank L has two arms 96 and 97 disposed at an angle of substantially ninety degrees and connected by a diagonal brace 98. At the end of its vertical arm 96 is a stud 99 on which is journaled a roll 100. The roll 100 is adapted to play up and down in a slot 101 formed in a member 102 secured to the traverse-bar E. Preferably the member 102 is constructed of sheet-metal with ears 103 bent around the sides of the traverse-bar E and welded or riveted thereto. The main portion of the member 102 extends below the bar E and is cut away at its center to provide two ears 105, 105 bent out to form the opposite, parallel sides of the slot 101 for the roll 100. On its outer sides the member 102 has its edges bent over 65 to provide two flanges or abutments 106, 106

which taper inwardly at the bottom and serve for a purpose as later explained.

At the outer end of the horizontal arm 97 of the bell-crank L is a block 110 pivoted on a pin 111 projecting from the side of the arm. The block 110 is fitted to slide in a rectangular slot or guiding-track 112 in a builder-arm O which is of channel like form in cross-section as shown more particularly in Fig. 4. Projecting from the side of the track- or builder-arm O is a stud or pin 114 pivotally mounted in a bearing 115, which depends from a bracket 116, and held in place by a cotter-pin 117, see Figs. 1 and 4. The bracket 116 is bolted to the side-flange 118 of the longitudinal frame-member or rail 2 which is of inverted-trough shape in cross-section as shown in Fig. 4. At the outer end of the builder-arm O is an extension 119 formed with a reversely curved cam 120 on its under side. Adapted to wipe across the cam 120 is a roll 121 journaled on a pin 122 carried at the end of a crank-arm 123. The crank-arm 123 is keyed to the end of a shaft 124 journaled in bearings 125—126 which project from the side of the right-hand bracket H. Fast on the inner end of the shaft 124 is a worm-gear 127 which meshes with a worm 128 journaled on a stud 129 projecting from the side of the bracket H. Also journaled on the stud 129 is a spur-gear 130 having its hub keyed to that of the worm 128 by means of the tongue-and-groove joint 131. The gear 130 meshes with another gear 132 which is fast on the upper drive-shaft S'. Through this train of gearing the shaft S' rotates the shaft 124 at a relatively slow rate of speed to turn the crank-arm 123 in the direction indicated by the arrow α , Fig. 3, whereby to cause the roll 121 to wipe across the cam 120. By means of this action the builder-arm O is caused to rock up and down on its pivot 114, thereby altering its angle of inclination to the horizontal, whereby to regulate the angular position of the bell-crank L as its block 110 travels in the track 112. The arm O is controlled by a spring 133 anchored at one end to a lug 134 on the left-hand bracket H and connected at its opposite end to an arm 135 reaching down from the under side of the arm. It will be noted from reference to Fig. 3 that the roll 121 on the crank-arm 123 engages first with the relatively short, convex portion 140 of the cam 120 to lift the track or builder-arm O against the action of its spring 133; but as the roll passes over the point 141 of the cam and travels around its concaved portion 142 the arm O will be allowed to rock downwardly under the influence of the spring 133. As the roll rides off from the end of the portion 142 of the cam 120 the downward movement of the arm O is arrested by a stop-screw 143 which strikes against the 130

flattened side 144 of the bearing 126 on the bracket H. The screw 143 is screwed into a lug 145 on the side of the cam 120 and is adjustable to regulate the extent of throw 5 of the arm O as required, a check-nut 146 being employed to lock it against unwarranted turning.

Projecting upwardly from the top of the builder-arm O is a relatively thin, flat spring 10 147 secured to an extension 148 of the cam 120 by means of a screw 149. The upper end of the spring 147 is bent into a curved abutment 150 which is adapted to engage the side of the flange 106 on the traverse-bar member 102 when the latter reaches the right-hand end of its throw, as viewed in Fig. 3. A corresponding spring 151 is fastened to the top of the rail 2 at 152 and formed with an abutment 153 at its upper end for engaging 20 the opposite flange 106 on the member 102 when the traverse-bar E moves in the reverse direction. The two springs 147 and 151 are thus caused to act as buffers to take the shock of the reciprocating motion of the traverse-bar E to assist the reversal of throw 25 of the latter at the ends of its traverse. The spring 151 is stationarily supported, since the left-hand extreme of traverse of the bar E is fixedly determined; while, on the other hand, the position of the spring 147 varies 30 with the displacement of the track or builder-arm O whereby to insure the proper coaction between the end of the spring and the member 102 when the extent of traverse 35 of the bar E is altered at its right-hand end. This shortening and lengthening of traverse of the bar E and its thread-guides G is effected through the periodical displacement 40 of the track or builder-arm O which rocks the bell-crank-lever L on the crosshead 86 during the continuous operation of the machine as more fully explained hereinafter. The coaction of these elements of the builder- or variable-traverse-motion is substantially 45 the same as that explained in my U. S. Patent No. 1,233,042, July 10, 1917, before referred to, although the construction and arrangement of the elements is somewhat different as will be seen.

50 The tension-devices, which apply tension to the yarns as they draw from their supply bobbins to the package being wound, may be of any suitable construction and as shown in Fig. 4 are arranged as follows: Secured to the flanges 118 of the horizontal side-rails 2 of the machine-frame F are a plurality of brackets or arms 155 which support two longitudinal bars 156 arranged on opposite sides of the machine. Only one of these bars is shown in Fig. 4, as both are arranged in the same manner on opposite sides of the frame F as shown in Fig. 2. Spaced at intervals along each bar 156 in appropriate relation to the several winding-units 60 are the tension-devices N. As shown

in Fig. 4 each tension-device N comprises two opposed disks or washers 157 rotatably mounted on a pin 158 with one or more weights 159 acting to press them together. Projecting from either side of the bar 156 70 are wire arms 160—160^a which are bent into loops at their ends to adapt them to guide the yarn or thread y as it leads between the tension-disks 157, 157. From the tension-devices N the yarns y lead to the thread-guides G across a sheet-metal apron or guard-plate J which extends the whole length of the machine, being fastened at the ends of arms 161 projecting from the front 75 of the bearing-brackets 12.

80 A horizontal rock-shaft 162 is journaled in bearings 163 in the arms 161 and pivoted thereon is a plurality of arms 164 extending outwardly beneath the tension-devices N and rearwardly toward the drive-rolls D, see 85 Fig. 10. Pivotaly mounted at the outer end of each arm 164 is a drop-wire 165 formed with a loop 166 at its upper end adapted to hook over the yarn y as it draws between the two guides 160—160^a. At the 90 side of each arm 164 is a stop-lever 167 formed at its end with a shoulder 168 adapted to be engaged by the lower end of the drop-wire 165. The hub 169 of the stop-lever 167 is split and secured fast on the 95 rock-shaft 162 by means of a binding screw 170. On the hub of the arm 167 is an ear 171 having a hole 172, into which is hooked the end of a rod or bar 173, see Fig. 4. The rod 173 extends laterally across the frame F and at its opposite end is connected to a lever corresponding with the stop-lever 167 to adapt it to serve as a means for oscillating the rock-shafts 162 on both sides of the machine. At its center is a pin 174 engaging 100 the upper, slotted end of a lever 175 which is pivoted at 176 to the side of the bracket H. The lower arm of the lever 175 is of bifurcated form arranged with its legs 177, 177 straddling the periphery of an eccentric 178 which is fast on the drive-shaft S'. As the eccentric 178 rotates with the shaft S' the lever 175 will be oscillated on its pivot 176 to reciprocate the rod or bar 173. This action 105 rocks the stop-levers 167 to oscillate the shafts 162 on the opposite sides of the frame F. Meanwhile the arms 164 are normally withheld from motion with the shaft 162 and levers 167 by means of their inner extensions 179 which serve as detent arms as 110 next explained.

115 Referring particularly to Figs. 10 and 11, each drive-roll D is provided with a cone-lifter Q adapted to be inserted between the surface of the cone and the periphery of 125 the roll to lift the package from driving contact therewith, whereby to arrest its rotation. The cone-lifter Q is formed with two arms 180—180 straddling the ends of the drive-roll D and pivoted on bushings q 130

projecting from the ends of the bearings 12, see Fig. 3, and surrounding the roll-shaft R. Connecting the arms 180—180 is an arcuate bridge-piece 181 formed with a relatively thin edge 182 adapted to be wedged in under the cone between its surface and that of the drive-roll D. Reaching downwardly from one of the arms 180 of the lifter Q is a lug 183 formed with a shouldered portion 184 adapted to engage the square end 185 of the inner arm 179 of the lever 164. A spring 186 fastened at one end to the lug 183 is anchored at its opposite end to a lug 187 on the arm 164 and normally tends to maintain the shouldered lug 183 on the lifter Q locked with the end of the detent-arm 179 as shown in Fig. 10. When, however, the end of the detent-arm 179 is rocked downwardly it will release the shoulder 184, whereby the spring 186 will turn the lifter Q on its axis to carry its portion 181 in under the package or cone being wound. This action raises the cone off from its drive-roll D to arrest its rotation in the manner and for the purpose as later explained. The operation of the cone-lifter Q is automatic and takes place upon the breakage or exhaustion of the yarn being wound. Referring to Fig. 4, when the yarn y fails or breaks, it will allow the drop-wire 165 to tilt, through the action of gravity, to engage its lower end with the shoulder 168 on the stop-lever 167. As before explained the lever 167 which is fast on the rock-shaft 162 is constantly oscillated from the eccentric 178 on the shaft S', and hence when the drop-wire 165 engages its end it will cause the arm 164 to be moved therefrom to depress its extension 179. The downward movement of the detent-arm 179 releases the lug 184 on the lifter Q which is then actuated from its spring 186 as previously explained. For resetting the lifter Q to release the cone while again engaging the detents 184 and 185 a bail-like handle 190 is provided on one of the arms 180. The bail 190 is preferably formed of wire with its inner end bent at right-angles and hooked into a hole 191 in the arm 180 of the lifter Q. The outer end of the bail 190 reaches through an opening 192 in the apron J and is bent into a loop 193 to provide a handle for pulling it outwardly to rock the lifter to remove it from under the cone.

The method of operation of the complete machine is as follows: The paper cone-tubes C are first applied to their supporting arms A and B by inserting their rounded noses c into the bearing-cups 50 and fitting their base ends over the conical bearing-rings 55, see Fig. 9. The hinged arrangement of the arms A adapts them to yield to provide for slipping the cone-tubes onto their supporting-rings 55, and when released their springs 49 cause them to press against

the nose ends of the tubes to hold their base ends snugly in place on the rings. During the operation of applying the cones to their supports the arms B may be suspended in raised position, if desired, by hooking the ends of the levers 72, shown in Fig. 4, around the tie-rod T. After the cone-tubes are in place the levers 72 are released to allow the arms B to drop and each tube will then come down against the bridge-piece 181 of the cone-lifter Q as shown in Fig. 11.

The yarns y to be wound into the cones draw off from supply-bobbins Y arranged below as shown in Fig. 2, and lead up across the guide-wires 160^a, between the tension-disks 157 and under the drop-wires 166 and guides 160, see Fig. 4. Thence the yarns y lead across the guard or apron J to the thread-guides G, being inserted through the slots g and secured to their respective cone-tubes C by winding their ends therearound. The threading up of the yarns may be done while the arms B are held suspended by their hook-levers 72 if desired, this being the preferred practice as more convenient for attaching the ends of the yarns to the cone-tubes. The machine is now ready for winding, each unit being started separately, and as all of the winding-mechanisms are the same, it will suffice to explain the method of operation of only one.

After the cone-tube C has been lowered into position above the drive-roll D the bail 190 is pulled forward and this action rocks the lifter Q on its axis to withdraw its bridge-piece 181 from under the tube, as shown in Fig. 10, whereby its surface will be engaged by the periphery of the roll D to be rotated therefrom. As the lifter Q is rocked around the shaft R against the tension of its spring 186 the end of its lug 183 rides over the curved end of the arm 179 until the detent-shoulders 184 and 185 come into locking engagement as shown in Fig. 10. Through this action the lifter Q will be held inoperative until released by the arm 179 as later explained.

The main drive-shaft S is rotated from the belt pulley P and, through the connections shown in Figs. 1 and 2, and previously described, drives the cam-shaft S' and drive-roll-shafts R R'. Referring now particularly to Figs. 3 and 4, the cam K rotates with the shaft S' and through the engagement of the roll 84 with its groove 83 acts to reciprocate the cross-head or slide 86 back and forth on its tracks 87—88. The slide 86 carries the bell-crank-lever L which is connected by its arm 96 to the traverse-bar E, and therefore a rectilinear, reciprocating motion will be imparted to the thread-guides G on the bar to traverse the yarn on the cone-tube C in spiral coils or helices in the manner well known to those versed in the art. As the bell-crank L moves back and

forth with the slide 86 the block 110 at the end of its horizontal arm 97 slides in the groove 112 of the track or builder-arm O and the position of the track determines the angular movement of the lever to regulate the shortening and lengthening of the traverse of the guides G in the manner as next explained.

The position of the track or builder-arm O is controlled by its spring 133 subject to the action of the crank-arm 123. The arm 123 turns in the direction indicated by the arrow α , Fig. 3, as rotated by its shaft 124 through the train of gearing 127, 128, 130, 132 driven from the cam-shaft S'. Through-out the greater portion of the building of the cone on its tube C the arm 123 is inoperative, its roll 121 revolving through that part of its orbit which is removed from the path of the cam 120 on the builder-arm O. During this period the track O will be inclined downwardly to the right with its stop-screw 143 resting against the flatted side 144 of the bearing 126. With the arm O remaining at rest in this position the block 110 on the arm 97 of the bell-crank L slides down the incline as the crosshead 86 moves to the right and hence the lever L will be rocked on its pivot 94 to give an added increment of movement to the traverse-bar E connected to its vertical arm 96. The full throw of the cam K is somewhat less than that required to traverse the thread-guide G from the base to the tip of the cone-tube C, that is to say, as herein shown the throw of the cam is three-quarters the full length of the cone wound on the machine. The additional one-quarter length of traverse of the thread-guide over and above the initial throw of the cam is therefore provided by displacing the bell-crank L angularly about its pivot 94 on the slide 86. In other words, the rocking of the lever L to the right augments the length of its normal stroke with the slide 86 and in this way an increment of movement is given to the traverse-bar E to provide the full length of traverse for the guides G. While the traverse-motion operates in this manner to wind the yarn the full length of the package the crank-arm 123 rotates about its axis at a relatively slow rate of speed until eventually the roll 121 at its end comes into engagement with the convex face 140 on the under side of the cam 120. This engagement immediately causes the builder-arm O to rock upwardly about its pivot 111 against the tension of its spring 133. In this way the inclination of the track or arm O is gradually reduced until finally it reaches a horizontal position with the center of its groove 112 in the plane of the axis of the pivot 94 of the bell-crank L. As the arm O swings upwardly on its pivot under the action of the roll 121 wiping along the cam face 140 the bell-crank L will undergo a

gradually diminishing displacement from the action of its block 110 in the guiding-groove 112. That is to say, the bell-crank L will be rocked to the right to a less extent during each traverse of the crosshead 86 to the right so that the length of traverse of the rod E will be correspondingly shortened at the small end of the cone. In this way the courses of the yarn coils laid onto the cone are progressively shortened or stepped back from its apex end whereby a thicker mass of yarn is built up at its base to effect the increase in taper on its surface. When the builder-arm O reaches the horizontal the angular displacement of the bell-crank will cease and the traverse of the bar E will be equal in extent to the full throw of the cam K. The tilting of the arm O does not stop at this point, however, but on the contrary continues until the right-hand end of the track is inclined upwardly above the horizontal. As the arm O rises above the horizontal its effect on the bell-crank L will be the opposite from that which it has when it is inclined downwardly. That is to say, the block 110 on the arm 97 will now travel up the incline of the track O to rock the bell-crank L to the left as the crosshead 86 slides to the right, and in this way the traverse of the bar E is still further shortened with respect to the throw of the cam K. As the roll 121 on the arm 123 reaches the "high" point 141 on the cam 120 the arm O will be raised to its maximum extent and the traverse of the guide G will have been shortened to substantially one-half the full length of the cone. From this point the traverse of the guide G starts to lengthen again as the builder-arm O is allowed to swing downwardly under the action of its spring 133. The downward movement of the arm O is controlled by the action of the roll 121 riding along the concave face 142 of the cam 120 and continues until the roll rides off the end of the cam and its stop-screw 143 once more comes into contact with the bearing 126. The traverse of the thread-guide G is thus gradually lengthened again until the maximum is reached which is equal to the full length of the package being wound. The guide G will then continue to be reciprocated with the full length of traverse until the crank-arm 123 has again moved around to bring its roll 121 once more into engagement with the outer end of the cam 120. In this manner the depositing of the coils of winding onto the cone takes place in cycles, the greater portion of the package being built up with layers of full length, interrupted at intervals by gradually shortened and lengthened courses of the coils. Through this method of laying the coils in place the body of the cone is built up with substantially wedge-shaped sections of shortened and lengthened courses intervening between the full length

layers and tending to cause the surface of the package to gradually assume an increased conicity or steeper pitch.

As the winding builds up in this manner 5 the increase in diameter of the mass causes the axis of the cone to recede from the drive-roll D while its surface remains constantly in contact therewith. As the cone rises its supporting arms A and B swing upwardly 10 on their pivots 29 and T' and meanwhile the axis of the cone becomes more and more inclined to the face of the drive-roll D, due to the increase in taper on the surface of the cone. During this change in the inclination 15 of the axis of the cone the ring 55 which supports the base end of the tube C will rock slightly on its bearings as provided for by the ball-and-socket joints of the bearing-hub 62, and the clearance of the stud 58 in its 20 bore 60, see Fig. 9.

As before stated the increase in inclination of the cone with respect to its drive-roll tends to cause its base to be formed convexly and its opposite end concaved. To 25 prevent this tendency from causing an abnormal concavity at the nose of the cone whereby its structure would be weakened the whole package is shifted bodily to the right by means of the cam 34 on the collar 32, see 30 Figs. 5 and 8, which acts against the lug 35 on the flange 36 of the arm B, as previously explained. Through this arrangement the shaping of the cone is determined and controlled within the prescribed limits to provide 35 the preferred formation of its ends.

The winding of the individual cones is arrested automatically by the action of the stopping-mechanism as next explained: Referring to Fig. 4, when a yarn *y* breaks or 40 its supply is exhausted its drop wire 165 will be tilted through the action of gravity to carry its lower end into the path of the stop-lever 167. The lever 167 is constantly oscillated from the rock-shaft 162 which receives its motion from the eccentric 178 on the shaft S', through the lever 175 and rod 173. The engagement of the lever 167 with the drop-wire 166 raises the arm 164 to depress its rearward extension 179. This action 45 releases its end 185 from the detent-shoulder 184 on the lug 183, see Fig. 10, and allows the cone-lifter Q to rock under the action of its spring 186. The bridge-member 181 of the lifter Q is thereby carried in under the cone or package to raise it away from the drive-roll D as shown in Fig. 11. In this manner the cone is free from driving contact with its drive-roll so that its rotation 50 will cease, and for convenience in repairing or piecing up the broken end it may be raised still further by hooking the lever 72 around the tie-rod T as previously explained. The rotation of the package may be arrested manually in the same way by simply lifting up 55 the end of the arm 164 to release the detents;

and to start the winding again it is only necessary to pull out the bail 190 to withdraw the cone-lifter Q and reengage its detent-shoulder 184 with the end 185 of the arm 179. It will be understood of course that 70 the thread-guides G reciprocate constantly during the continued operation of the machine, it being unnecessary to arrest their motion to thread them since if the yarn is drawn taut between the cone and the tension-device the guide will pick it up as it lays across the top of the apron J, see Fig. 10.

Various modifications might be made in the form and construction of the parts of my improved machine without departing 80 from the spirit or scope of the invention; therefore, without limiting myself to the exact embodiment shown and described, what I claim is:—

1. In a cone-winding machine, the combination with means for rotatably supporting the cone, of a rotatable drive-roll for driving the cone, a reciprocable thread-guide for traversing the yarn on the cone, a cam, a crosshead reciprocated from the cam, a bell-crank-lever pivoted on the crosshead and connected to reciprocate the thread-guide, a pivoted builder-arm formed with a track, means on the bell-crank-lever slidable on said track, and a crank-arm adapted to engage the builder-arm to rock the latter on its pivot to alter the position of the track to cause the bell-crank-lever to be displaced about its axis on the crosshead during the reciprocation of the latter to vary the length 100 of traverse of the thread-guide reciprocated therefrom.

2. In a cone-winding machine, the combination with means for rotatably supporting the cone, of a rotatable drive-roll for driving the cone, a thread-guide for traversing the yarn on the cone, a cam, a crosshead reciprocated from said cam, a bell-crank-lever pivoted on the crosshead and connected to traverse the thread-guide, a rockable builder-arm formed with a track, means on the bell-crank slidable on said track, a rotating crank-arm, and a roller at the end of said crank-arm adapted to engage the builder-arm to rock the latter up and down on its pivot to displace the bell-crank-lever on the crosshead during its reciprocation therewith whereby to alternately shorten and lengthen the traverse of the thread-guide at one end of its throw.

3. In a winding machine, the combination with means for rotatably supporting the package, of a drive-roll for driving the package, a thread-guide for traversing the yarn on the package, a cam, a crosshead reciprocated from said cam, a bell-crank-lever pivoted on the crosshead with one of its arms connected to the thread-guide, a pivoted builder-arm formed with a guiding-track and a cam-face, means on the opposite arm 125

of the bell-crank fitted to slide on the track, a rotating crank-arm adapted to wipe across the cam-face on the builder-arm to oscillate the latter about its pivot, a spring 5 for maintaining the builder-arm in position to be engaged by the crank-arm, and means to limit the movement of the builder-arm under the action of the spring.

4. In a winding machine, the combination 0 with a traverse-cam, of a crosshead reciprocated from said cam, a bell-crank-lever pivoted on said crosshead, a traverse-bar connected to one of the arms of the bell-crank-lever, a builder-arm formed with a guiding- 5 track and a cam-face on its side, means on the other arm of the bell-crank adapted to slide in the track of the builder-arm, a crank-arm, means to rotate the crank-arm, and a roll at the end of said crank-arm 0 adapted to wipe along the cam-face on the builder-arm to oscillate the latter on its pivot to displace the bell-crank-lever on the crosshead as it reciprocates therewith whereby to vary the length of throw of the 5 traverse-bar at one end of its traverse.

5. In a winding machine, the combination with a sliding crosshead, of means to reciprocate said crosshead, a lever pivoted on the crosshead, a thread-guide connected to be traversed from the lever, controlling-means for displacing the lever about its pivot on the crosshead during its reciprocation therewith, a cam for operating said controlling-means, and a rotating crank-arm adapted to 5 intermittently engage the cam to shift the position of the controlling-means whereby to displace the lever on the crosshead to cause a gradual shortening and lengthening of the traverse of the thread-guide during recurring cycles of its operation.

6. In a winding machine, the combination with a sliding crosshead, of means to reciprocate the crosshead, a bell-crank-lever pivoted on the crosshead to be reciprocated therewith, a thread-guide connected with said lever to be traversed therefrom, a builder-arm engaging the lever to displace it about its pivot to effect a differential motion between the thread-guide and cross- 0 head, a cam formed integral with said builder-arm, and means adapted to engage the cam to move the builder-arm to regulate the displacement of the bell-crank-lever whereby the thread-guide is reciprocated 5 normally with a traverse of maximum extent and its throw is periodically shortened at recurring intervals during its operation.

7. In a winding machine, the combination with a reciprocable slide, of means to reciprocate the slide, a lever pivoted on the slide to be reciprocated therewith, a thread-guide connected to the lever to be traversed therefrom, a track engaging the lever to cause it to be rocked on the slide during its reciprocation therewith to regulate the extent of

traverse of the thread-guide, a cam on said track, a rotating crank-arm, and means carried by said crank-arm to wipe along the cam on the track to change the position of the latter to displace the lever on the slide 70 whereby to cause a gradual shortening and lengthening of the traverse of the thread-guide during recurring periods of its operation.

8. In a winding machine, the combination 75 with a reciprocating crosshead, of a bell-crank lever pivoted on said crosshead, a thread-guide connected to be reciprocated from said lever, a pivoted guiding-track, means on the lever engaging said track to 80 slide thereon, a cam on said track, a rotating crank-arm adapted to engage the cam to rock the track on its pivot to vary its inclination below and above the horizontal, and means for holding the track normally in an 85 inclined position before the crank-arm engages with its cam.

9. In a winding machine, the combination 90 with a reciprocating crosshead, of a bell-crank-lever pivoted on the crosshead, a thread-guide connected to be reciprocated from said lever, a swinging track engaging the lever to rock it on the crosshead during its reciprocation therewith, means to maintain the track normally in a fixed position to 95 cause the lever to reciprocate the guide with a maximum extent of throw, and a rotating crank-arm adapted to periodically engage with the track to move it from its fixed position to effect a shortening of the traverse 100 of the thread-guide during recurring intervals of its operation.

10. In a winding machine, the combination 105 with a reciprocating crosshead, of a lever pivoted on the cross-head, a thread-guide connected to be reciprocated from said lever, a swinging track engaging the lever to rock it on the crosshead during its reciprocation therewith, and a rotating crank-arm for periodically engaging the track to 110 displace it angularly with respect to the path of the bell-crank-lever to alter the length of stroke of the thread-guide during recurring cycles of its operation.

11. In a winding machine, the combination 115 with a reciprocating crosshead, of a cam for reciprocating the crosshead, a bell-crank-lever pivoted on the crosshead, a thread-guide connected to be reciprocated from said lever, a track engaging the lever 120 to rock the latter during its reciprocation with the crosshead to alter the length of traverse of the thread-guide, a crank-arm for displacing the track with respect to the path of the lever, and means to rotate said crank-arm from the traverse-cam at a reduced rate of speed.

12. In a winding machine, the combination 125 with a frame for supporting a plurality of winding-units, of a traverse-bar re- 130

- ciprocable in bearings on the side of the frame, a plurality of thread-guides carried by said bar in correlation to the several winding-units on the frame, a single traverse-cam, means to drive said cam, a cross-head reciprocated from said cam, a lever pivoted on said crosshead and connected to reciprocate the traverse-bar, a track engaging the lever to displace the latter on the cross-head during its reciprocation therewith to regulate the length of throw of the traverse-bar, and a rotating crank-arm operated from the cam driving means to adapt it to periodically engage the track to change the position of the latter to effect a displacement of the bell-crank-lever in the manner and for the purpose substantially as described.
13. In a winding machine, the combination with a frame comprising end standards and longitudinal side-rails, of two opposite traverse-bars extending the length of the frame and slidable in bearings on the side-rails, a drive-shaft rotatable in bearings below the side-rails, a traverse-cam mounted on said shaft to rotate therewith, cross-heads connected to be reciprocated from said cam on the opposite sides thereof, bell-crank-levers pivoted on said crossheads with their upper arms connected to the traverse-bars, tracks pivoted on the side-rails on the opposite sides of the cam, means on the bell-crank-levers slidable on said tracks, a cross-shaft driven from the cam-shaft, and crank-arms at the ends of said cross-shaft adapted to engage the tracks to rock the latter on their pivots to progressively displace the bell-crank-levers during their reciprocation whereby to alter the length of throw of the traverse-bars.
14. In a winding machine, the combination with a traverse-cam, of a crosshead reciprocated from said cam, a bell-crank-lever pivoted on said crosshead, a track pivoted on a fixed axis in the path of traverse of the crosshead, said track formed with a reversely curved cam-face on its side, means carried by the bell-crank-lever to engage the track to slide thereon, a thread-guide connected to be reciprocated from the bell-crank-lever, a rotating crank-arm, a roll at

the end of the arm adapted to wipe along the cam-face on the track, and a spring for maintaining the track with its cam-face engaged by the roll whereby an alternately upward and downward tilting motion is imparted to the track in the manner and for the purpose substantially as described.

15. In a winding machine, the combination with a traverse-cam, of a crosshead reciprocated from said cam, a bell-crank-lever pivoted on the crosshead to be reciprocated therewith, a thread-guide connected with the bell-crank-lever to be traversed therefrom, a track engaging the bell-crank-lever, means to rock the track to cause it to displace the bell-crank-lever on the crosshead to vary the length of traverse of the thread-guide, a fixed buffer-spring adapted to engage the thread-guide at one end of its traverse, and a second buffer-spring carried by the track to be moved thereby into position to engage the thread-guide at the opposite end of its traverse during the shortening and lengthening of its stroke.

16. In a winding machine, the combination with the frame thereof, of opposite brackets depending from the sides of the frame, a cam-shaft rotatable in bearings in said brackets, a cam fixedly mounted on said shaft, horizontal tracks extending between the brackets at the side of the cam, a crosshead mounted to slide on said tracks and connected to be reciprocated from the cam, a bell-crank-lever pivoted on the crosshead, a traverse-guide connected to be reciprocated from said bell-crank-lever, a track pivoted on a fixed axis at the side of the cam and engaging the bell-crank-lever to rock the latter on the crosshead, a cross-shaft mounted in bearings on one of the brackets, a train of gearing connecting said cross-shaft to be driven from the cam-shaft, and a crank-arm mounted on said cross-shaft to be rotated therewith to adapt it to engage the track whereby to periodically rock the latter to displace the bell-crank-lever about its axis during its reciprocation with the crosshead.

In testimony whereof I affix my signature.
GEORGE W. FOSTER.
